No. 36,784.

Patented February 9, 1904.

UNITED STATES PATENT OFFICE.

CHARLES A. WARNER, OF NEW YORK, N. Y.

DESIGN FOR A CLOCK CASE AND SUPPORT.

SPECIFICATION forming part of Design No. 36,784, dated February 9, 1904.

Application filed June 30, 1902. Serial No. 113,883. Term of patent 7 years.

To all whom it may concern:

Be it known that I, CHARLES A. WARNER, a citizen of the United States, and a resident of New York, county of New York, and State of New York, have invented a new, original, and ornamental Design for a Clock Case and Support, of which the following is a specification, reference being had to the accompanying drawing, forming a part thereof.

10 The design is illustrated by the accompany-

ing drawing, which shows a perspective view of the clock case and support.

I claim—

The ornamental design for a clock case and support, as shown.

CHARLES A. WARNER.
